UNITED STATES PATENT OFFICE.

PHILIP DIEHL AND HERMANN EICHHORN, OF ELIZABETH, NEW JERSEY, ASSIGNEES
TO THE SINGER MANUFACTURING COMPANY, A CORPORATION OF NEW JERSEY.

FEED-REGULATOR FOR SEWING-MACHINES.

1,118,271.

Specification of Letters Patent. Patented Nov. 24, 1914.

Application filed December 12, 1912. Serial No. 736,247.

To all whom it may concern:

Be it known that we, PHILIP DIEHL and HERMANN EICHHORN, citizens of the United States, residing at Elizabeth, in the county 5 of Union and State of New Jersey, have invented certain new and useful Improvements in Feed-Regulators for Sewing-Machines, of which the following is a specification, reference being had therein to the 10 accompanying drawings.

This invention has for its object to provide the feeding mechanism of a sewing machine with controlling or regulating means whereby the normal work-advancing 15 movements of the mechanism may be reversed to produce a retrograde movement of the work equal or proportionate to its normal rate of advancing movement.

As embodied in the regular four-motion 20 feeding mechanism of a Singer sewing machine, the link-bar connected with the feed rock-shaft, and deriving its vibratory movements from a cam upon the main-shaft, is provided intermediate its ends with a fulcrum 25 connected with a swinging link whose fulcrum is sustained by and eccentrically to the feed-regulator rock-shaft which extends through the wall of the bracket-arm and has upon its outer end an operating lever for 30 turning it. The feed-regulator rock-shaft has also fixed thereon a stop-member extending across and in both directions from its axis of movement and adapted for engagement upon either side of said axis with the 35 point of a stop-screw also journaled in the bracket-arm. The head of the stop-screw exterior to the bracket-arm is formed with an annular series of closely spaced notches adapted to be entered by similarly spaced 40 projections formed upon the adjacent face of a cap adjustably secured thereon. The said cap is provided with a series of peripheral notches adapted to be entered by the conical end of a spring-pressed detent-pin 45 journaled in the bracket-arm and adapted to arrest the circular movement of the stop-screw in different positions of the latter for determining its operative relation with the stop-member of the feed-regulating rock- 50 shaft. The cap is provided with a stop-pin adapted for engagement with the said spring-pressed detent-pin to prevent the turning of the stop-screw through more than

a complete rotation, so that the position of the stop-screw corresponding with a certain 55 length of stitch will be correctly shown by means of an indicating device including a properly graduated circular scale upon or adjacent and concentric with the cap.

In the accompanying drawings, Figure 1 60 is a side elevation of the rearward end of a sewing machine embodying the present improvements, with the bracket-arm and bed-plate in section, and Fig. 2 is a transverse section of the same looking forwardly. Fig. 65 3 is an enlarged perspective view representing the feed-regulating device, and Fig. 4 a similar view showing the feed-regulating rock-shaft with its stop-member and the stop-screw coöperating therewith. Figs. 5 70 and 6 are perspective views showing respectively the cap and the stop-screw to which the cap is applied.

As represented in the drawings, the sewing machine frame comprises the bed-plate 75 1 from which rises the hollow standard 2 with tubular lateral arm 3 in which is journaled the main-shaft 4 carrying the feed-lift crank 5 and the feed-actuating cam 6, and provided with the usual balance-wheel 80 7 with grooved belt-wheel 8.

Embracing the feed-actuating cam 6 is the yoke 9 formed at the upper end of the link-bar 10 which extends downwardly through the hollow standard 2 of the bracket-arm 85 13 and is pivotally connected by means of the screw-stud 11 with the crank-arm 12 upon the rearward end of the feed rock-shaft 13 which has at its forward end the usual upwardly extending arms 14 carrying pivotal 90 screw-pins 15 by means of which it is connected with the feed-bar 16 upon which is secured the usual feed-dog 17. The opposite end of the feed-bar 16 is formed with the usual fork 18 embracing the roller-stud 19 95 carried by the lateral arm 20 of the feed-lift rock-shaft 21 provided upon its rearward end with the lateral crank-arm 22 pivotally connected by means of the screw-pin 23 with the lower end of the rod 24 which is formed 100 at its opposite end with the strap 25 embracing the feed-lift crank 5.

Secured in position by means of the clamp-nut 26 within the apertured boss 27 of the link-bar 10 slightly below its yoke 6 105 is the fulcrum-stud 28 embraced by the

apertured boss 29 at one end of the supporting link 30 whose opposite end is similarly provided with an apertured boss 31 embracing the stud-pin 32 sustained by a crank-
5 arm 33 which is fixed upon the feed-regu-
lator rock-shaft 34. The feed-regulator
rock-shaft is journaled within the bearing
boss 35 of and extends through the wall of
the standard 2, having secured upon its
10 outer end by means of the set-screw 36 and
locking screw 37 the hub 38 of the operating
lever 39.

As represented in the drawings, the crank-
arm 33 is provided with the threaded aper-
ture 33' to receive the similarly threaded
stud-pin 32 disposed eccentrically to the feed
regulator rock-shaft, and has formed inte-
gral therewith the plate or disk 40 having
the angularly disposed edges 41 and 42 ar-
20 ranged transversely to and upon opposite
sides of the axis of the rock-shaft 34. The
plate 40 constitutes a stop-member whose
operative shoulders 41 and 42 are adapted for
engagement with the rounded inner end por-
25 tion 43 of the stop-screw 44 which is jour-
naled within a suitably threaded aperture
in the bearing boss 45 of the standard 2
transverse to the rock-shaft 34.

The enlarged outer portion or head 46 of
30 the stop-screw is shown provided in its
outer face with the annular groove 47 be-
tween which and its periphery it is provided
with a series of radial nicks or serrations 48,
and within which it is provided with a
35 threaded socket 49. Secured to the head 46
of the stop-screw by means of the fastening
screw 50 is the cup-shaped cap 51 formed
with knurled periphery and having upon its
inner face surrounding the screw-aperture 52
40 the annular series of radial projections 53
corresponding in spacing with the nicks 48
of the head 46 and adapted to enter the same
when the cap 51 is secured in position thereon.
By this means, the cap 51 may be applied to
45 the stop-screw head 46 in the required posi-
tion thereon, in which it is locked by the
interengaging projections 53 and nicks 48
with the parts clamped in position by means
of the screw 50.

50 The cap 51 has in its inner edge a series
of notches 54 adapted to be entered by the
conical point of a detent-pin 55 slidingly
fitted within a suitable socket in the bearing
lug 45 and having its reduced inner portion
55 56 surrounded by a spring 57 interposed be-
tween the head of the pin 55 and the bottom
of the surrounding socket, whereby the
spring is normally pressed outwardly into
yielding engagement with the inner edge of
60 the cap 51. Between the notches 54 at one
side the cap is provided with a stop-pin 58
which is adapted to contact with the oppo-
site sides of the detent-pin 55 when the cap is
turned into opposite extreme positions so
65 that it is limited to slightly less than a com-

plete rotation in its control of the position
of the stop-screw relatively to the stop-
member 40.

The stop-screw cap is shown in the draw-
ings provided in its outer face with a circu-
lar scale graduated to correspond with the
spacing apart of the detent-notches 54. The
dial thus produced is provided with figures
to indicate the number of centimeters of the
stitch-lengths corresponding with the ex-
treme throw of the feed-regulator rock-
shaft 34 when either stop-shoulder 41 or 42
is in contact with the stop-screw in its in-
dicated position. By means of the circular
adjustment of the cap 51 upon the head of 80
the stop-screw, the cap may be secured in
position with its dial and stop-pin properly
located after the screw has been turned into
a corresponding initial position relatively to
the stop-member 40 for the initial length of 85
feed, and the construction is therefore
adapted to correct in this respect any lack of
uniformity in the lengths of the screws or
positions of the operative shoulders 41 and
42 of the stop-member in manufacturing 90
such devices in large quantities. As the
feed-length adjustment is formed upon a
normally stationary part, and that part has
indicating means for showing the length of
stitches corresponding with its various posi-
tions, it is evident that the length of the
stitches may be adjusted by merely turning
the stop-screw to the desired position, the
operating lever 39 being only then required
to be thrown from one to the other of its 100
extreme positions limited by the stop-screw.
to cause the feed to impart advance or
retrograde movements to the work corre-
spondingly.

Having thus set forth the nature of the 105
invention, what we claim herein is:—

1. In a sewing machine, the combination
with the frame comprising a bed-plate and
a bracket-arm formed with a hollow stand-
ard and an overhanging tubular member ex-
tending laterally therefrom, a rotary shaft
journaled in said tubular member and car-
rying a feed-actuating element, a feed rock-
shaft arranged below the bed-plate and op-
eratively connected with a feeding element,
a crank-arm upon said rock-shaft, a link-
bar pivotally connected at one end with
said crank-arm and extending upwardly
through said standard and operatively con-
nected at its opposite end with the feed-
actuating element, and a laterally movable
fulcrum for said link-bar, of a rock-shaft
for sustaining said fulcrum journaled in
and extending through the wall of said
standard and provided with a stop member
extending oppositely across its axis of move-
ment, an operating lever secured upon the
fulcrum-sustaining rock-shaft exterior to
said standard, and a stop-screw journaled
in and extending through the wall of said 120
125
130

- standard transversely to the fulcrum-sustaining rock-shaft and adapted for engagement with said stop member upon either side of its axis of movement.
- 5 2. In a sewing machine, the combination with the frame, including a hollow standard, of feeding mechanism, a feed regulating device comprising a rock-shaft, a lever applied to said rock-shaft, a stop-member sustained by said rock-shaft and extending oppositely across the latter's axis of movement, a stop-screw journaled in a fixed bearing and adapted for engagement with said stop-member upon either side of its
- 10 axis of movement, said screw being provided with a cap having an annular series of notches, a socket formed in said standard, an endwise movable detent pin fitted within said socket, and a spring supported
- 15 by said standard and adapted to press said pin into engagement with the notches of said cap.
3. In a sewing machine, the combination with feeding mechanism, of a feed-regulating device comprising a rock-shaft, a lever applied thereto for turning it, a stop-member sustained by said rock-shaft and extending oppositely across the latter's axis of movement, a stop-screw journaled in a fixed
- 20 bearing and adapted for engagement with said stop-member upon either side of its axis of movement, yieldingly operating detaining means applied to said screw and acting at predetermined intervals in a
- 25 rotary movement thereof, and means for preventing the turning of said stop-screw through more than a complete rotation.
4. In a sewing machine, the combination with feeding mechanism, of a feed-regulating device comprising a rock-shaft, a lever applied thereto for turning it, a stop-member sustained by said rock-shaft and extending oppositely across the latter's axis of movement, a stop-screw journaled in a
- 30 fixed bearing and adapted for engagement with said stop-member upon either side of its axis of movement, yieldingly operating detaining means applied to said screw and acting at predetermined intervals in a
- 35 rotary movement thereof, and means adapted for operative engagement with an element

of said detaining means for preventing the turning of said stop-screw through more than a complete rotation.

5. In a sewing machine, the combination with feeding mechanism, of a feed-regulating device comprising a rock-shaft, a lever applied thereto for turning it, a stop-member sustained by said rock-shaft and extending oppositely across the latter's axis of movement, a stop-screw journaled in a fixed bearing and adapted for engagement with said stop-member upon either side of its axis of movement, said screw being formed with a head having an annular series of notches, a cap applied to said head and formed in its adjacent face with projections adapted to enter said notches in the screw-head, means for removably securing said cap to the screw-head, and detaining means operating yieldingly to restrain the rotation of said stop-screw at predetermined points, and including a non-rotating detent member and an annular series of coöperating elements carried by said cap.

6. In a sewing machine, the combination with a standard, of feeding mechanism, a feed regulating device comprising a rock-shaft projecting within said standard and operatively connected with said feeding mechanism, an operating lever secured upon said rock-shaft exterior to said standard, a stop-device comprising interengaging members mounted respectively upon said rock-shaft and the standard, one of said members being in the form of a stop-screw movable toward and from the axis of movement of the rock-shaft and provided with an annular series of notches, a spring-pressed endwise-movable detent pin fitted within a socket formed in the standard and adapted to engage the said notches, and an indicating device including a graduated dial substantially concentric with the stop-screw for indicating the limits of movement of the rock-shaft.

In testimony whereof, we have signed our names to this specification, in the presence of two subscribing witnesses.

PHILIP DIEHL.
HERMANN EICHHORN.
